UNITED STATES PATENT OFFICE

FRANCIS J. LAPONTE, OF ANN ARBOR, MICHIGAN

BROACHING MACHINE

Application filed September 6, 1928. Serial No. 304,247.

My invention has for its object to produce a broaching machine wherein the draw or the punch is produced hydraulically by pressure over a relatively large area, while the return is produced by pressure over a small area with consequent quick return between broaching operations. In the preferred form of construction embodying my invention, a fixed piston and a movable cylinder are used, having two pressure areas of different sizes. The piston supporting member extends through one end of the cylinder which reduces the volume within and of the pressure area on the end of the cylinder on that side of the piston, while the other end of the cylinder has the full effective area of the interior of its cross section. The first produces a magnified movement to produce a rapid change of one dimension of the volume of oil introduced into the cylinder which produces a quick stroke of the cylinder upon the introduction of a small quantity of oil, and the second produces a powerful broaching stroke. Thus, by my invention, liquid of substantially uniform pressure per square inch may be used and yet produce a powerful working stroke and a quick return stroke.

The invention also has for its object to provide a hydraulic pressure means at a point above the face plate used for retaining the object while being broached, which produces a draft as between the actuating pressure and the point of resistance to the movement induced by that pressure, and eliminates or reduces the variable deformation occurring by reason of the elasticity of interconnected parts where the actuating pressure point is located below the face plate. The invention also eliminates a large part of the exteriorly located piping through which the transmission liquid is transposed and thus the machine not only presents an attractive appearance, but also, its parts are economically used to perform double functions which materially reduces the number of parts and at the same time increases its efficiency.

The invention may be contained in broaching machines that vary in their details, and to illustrate a practical application of the invention, I have selected a vertical broaching

machine containing the invention as an example of such structures, and shall describe it hereinafter. The broaching machine selected is shown in the accompanying drawings.

Fig. 1 illustrates a front view of the broaching machine. Fig. 2 illustrates a side view of the machine. Fig. 3 illustrates a top view of the machine. Fig. 4 illustrates a rear view of the base of the machine. Fig. 5 illustrates a view of a section taken on the plane of the line 5-5 indicated in Fig. 2. Fig. 6 illustrates a view of a section taken on the plane of the line 6-6 indicated in Fig. 5. Fig. 7 illustrates a view of a section taken on the plane of the line 7-7 indicated in Fig. 3. Fig. 8 illustrates a view looking upwards from beneath the base of the machine.

The machine is provided with a base 1 on which the parts of the machine are mounted. It has a frame that is composed of three vertical standards or rods 2 and 3. The standards 2 are secured to blocks 4 that are bolted to the base 1, while the standard 3 is secured to the base by a suitable nut 5. The upright standards 2 and 3 are connected together by a suitable triangular frame 7 which, together with the standards, operates to increase the rigidity of the superstructure of the machine.

The standards 2 also form guides for the crosshead 8 that is adapted to slidably move along the standards. They also form a support for the face plate 9. The face plate 9 is provided with openings through which the standards 2 extend. It is secured in position by means of a pair of split collars 10 that may be located in channels 11 formed in the standards 2 and also in recesses 12 formed in the upper surface of the face plate 9 where the standards 2 pass through the face plate 9. The face plate 9 may also be further secured in position by means of the key bolts 13. Thus there is produced a means for securely locking the face plate 9 in position as against the pressure that it is subjected to by the machine during the broaching operations. If it is desired to adjust the face plate 9, relative to the other parts of the machine, it may be done by forming a plurality of channels 11 in order to provide for securing the face

plate 9 at different positions along the standards 2, depending on the stroke or initial position that it is desired to give the cross-head.

5 The crosshead 8 slidably moves along the standard 2 above the face plate 9 and is operated by a pair of cylinders 20 that are connected to the outer ends of the crosshead 8. A tool chuck or head 21 projects downward 10 from the crosshead 8 towards the top of the face plate 9. It may be provided with the usual key slot 22 into which a key may be inserted for locking the broaches to the cross-head 8. The work is supported on the under 15 side of the face plate 9 and the broach extends through a suitable opening formed in the face plate 9, in the manner well known in the art. Thus, the upper ends of the cylinders 20, which are subjected to hydraulic 20 pressure, are located well above the face plate 9.

The cylinders 20 are provided with cylinder heads 23 that may be threaded into the upper ends of the cylinders 20. They are provided with threaded hubs 24 that extend through the crosshead 8, and are secured to the crosshead by means of the nuts 25. Stationary pistons 26 are located within the cylinders 20 and are provided with the usual 25 sealing piston rings 27. The pistons 26 are supported in position by means of hollow cylindrical stems or members 28 that protrude through the lower ends of the cylinders. Suitable glands or packing rings 29 close the spaces formed between the walls 30 of the members 28 and the cylinders 20. There is thus formed large pressure areas for the actuation of the cylinders 20 at their upper ends, namely, on the inner surface of the cylinder heads 23, and also a very much 35 smaller volume per unit of length of the cylinders in their lower parts, namely, within the annular chamber located intermediate the cylindrical surface of the members 28 and the inner surfaces of the cylinders 20. This 40 gives a powerful upward stroke of the cylinders and of the crosshead during the broaching operation and a very quick return, since the volume changes but a small amount per 45 unit of length of stroke of the cylinder. 50

The pistons 26 are connected to the blocks 4. The hollow piston supporting members 28 extend through the blocks 4 and are secured by nuts 35 that are threaded onto the ends 55 of the hollow cylindrical members 28. A pair of pipes 36 and 37 extend through the cylindrical piston supporting members 28 to the pistons 26. The pipes 36 are connected through bores 38 to points above the pistons, 60 while the pipes 37 are connected through bores 39 to points below the pistons. Thus liquid conveyed through the pipes 36 are directed into the upper ends of the cylinders and the pressure that it is subjected to is 65 transmitted throughout the areas of the cylin-

der heads 23. This is during the working stroke of the machine. During the return stroke of the machine, the liquid is transmitted through the pipes 37 and into the annular chambers formed between the cylindrical members 28 and the cylinders 20. By reason of the different rates of change in volume of the liquid thus transferred in these two strokes, the pipes 37 may be made much smaller than the pipes 36 which enables the use of much smaller pipes 37 and, consequently, much larger pipes 36 within the confines of the cross sectional area of the interior of the cylindrical piston supporting members 28.

70 The pipes 36 and 37 are connected to a two-way valve for directing liquid from a source of supply of liquid under pressure to the cylinders 20 and to exhaust the liquid from the cylinders 20. At the same time that the liquid is being transmitted through one of the pipes 36 or 37 to each cylinder, the other of the pipes is being used to exhaust the cylinder to which it is connected.

75 The pipes 36 are connected together and the pipes 37 are connected together and, by suitable T's and elbows, the pipes are connected to the four-way valve 45 having a liquid inlet 46 and a liquid outlet 47 which may be connected, respectively, to the outlet and intake of a suitable pump, or other source of supply of liquid under pressure, in the manner well known in the art.

80 The operations of the machine are thus controlled by manipulation of the valve 45. In the form of construction shown, the valve 45 may be operated manually to start the broaching operation and then automatically upon the completion of the broaching stroke and again automatically to stop the machine.

85 The valve 45 may be controlled by two levers, such as the pedal lever 50 and the hand lever 51. The pedal lever 50 is pivotally supported in a pair of ears 52 and a boss 53 that project from the walls of the base 1 of the machine. The pedal lever 50 is provided with two arms 54 and 55. The arm 54 is connected by a link 56 to the hand lever 51 and, consequently, the hand lever 51 is moved with the pedal lever 50 and also the pedal lever 50 is moved when the hand lever 51 is operated.

90 The arm 55 of the pedal lever 50 is connected to the valve 45 by means of the link 57 and so that when the pedal lever 50 is depressed, the valve 45 is rotated so as to connect the pipe 36 with the inlet pipe 46 and the pipe 37 with the pipe 47 which is the outlet pipe of the machine. This produces a pressure on the cylinder heads 23 which raises the crosshead 8.

95 A rod 58 is connected to the crosshead 8. It extends through a slot formed in the hand lever 51. If desired, the hand lever 51 may be made in the form of a Y and the end of the rod 56 may be located within the arms of the Y and the rod 58 may extend between the 100

arms of the Y and pass through the hand lever 51. The rod 58 is provided with a pair of adjustable stops 59, one located above and the other located below the hand lever 51. Therefore, as the crosshead 8 moves to a certain point, one of the stops 59 engages the hand lever 51 which has been depressed by the movement of the pedal lever 50 or by depression of the hand lever 51 to start the broaching operation, and, by reason of the upward movement of the hand lever 51 produced by the stop 59, the pedal lever 50 is raised by the movement of the link 56. The lever 50 operates the valve 45 to establish connection between the source of supply of liquid under pressure through the pipe 46 to the pipe 37, while at the same time the outlet pipe 47 is connected with the pipe 36. The pressure of the liquid is thus communicated to the lower end of the cylinder 20, while the upper end of the cylinder is exhausted and the crosshead 8 descends. This may continue its downward movement until the upper stop 59 operates on the lever 51 and the pedal 50 to locate the valve 45 in a closed position. If desired, however, the valve 45 may again be operated to cause the machine to perform its broaching stroke.

Thus, I have provided an exceedingly efficient broaching machine having relatively few parts and one which may be rendered automatic as well as one that is subject to constant manual control, and one which has a powerful broaching stroke and a quick return.

I claim:

1. In a vertical broaching machine, the combination of a face plate for maintaining the work in position, a reciprocable crosshead located above the face plate, means for connecting a broaching tool to the crosshead, a base below the work plate cylinder heads connected to the said crosshead on each side of the broach connecting means, cylinders connected to the said cylinder heads, pistons located in the cylinders the top of the pistons located above the face plate, a pair of piston sleeves attached to said base for supporting the said pistons, each of the pistons having passageways therethrough, one connecting the exterior of the sleeve at a point on one side of the piston, the other connecting at a point intermediate the piston and the said cylinder head, the cylinders having walls surrounding the said sleeves.

2. In a broaching machine, a base, a work plate, a pair of vertically extending rods secured in the base and to the work plate and extending through the work plate to a point above the work plate, a crosshead secured to the upper end of the said rods, a drawhead located intermediate the work plate and the crosshead and guided in its movements by the rods, a pair of cylinders connected to the drawhead, pistons located in the cylinders

and shells connected to the pistons and secured in the base, the pistons having passage-ways communicating with opposite sides of the pistons for conducting a fluid to the cylinders on opposite sides of the pistons.

In witness whereof I have hereunto signed my name to this specification.

FRANCIS J. LAPOINTE.
